UNITED STATES PATENT OFFICE

2,438,401

PREPARATION OF CYCLOPENTADIENE

Robert M. Kennedy, Drexel Hill, and Stanford J. Hetzel, Cheltenham, Pa., assignors to Sun Oil Company, Philadelphia, Pa., a corporation of New Jersey

No Drawing. Application February 26, 1946,
Serial No. 650,394

2 Claims. (Cl. 260—666)

1

This invention relates to dehydrogenation and cyclization of hydrocarbons. Specifically it relates to the dehydrogenation and cyclization of n-pentane, 1-pentene, 2-pentene and 1,3 pentadiene to 1,3 cyclopentadiene. More specifically, the invention is concerned with a commercially feasible process for the conversion of n-pentane to 1,3 cyclopentadiene.

The conversion of pentane to 1,3 cyclopentadiene is considered to take place by way of, say, 1-pentene and 1,3 pentadiene. The yield of 1,3 cyclopentadiene will be higher when the charging stock requires the least amount of dehydrogenation. Accordingly, the invention will be described with reference to the conversion of 1,3 pentadiene to 1,3 cyclopentadiene to which it is pre-eminently suited. The reactions in the foregoing enumerated steps can be represented as follows:

According to the invention, 1,3 pentadiene in pure form, or admixed with normal pentane and/or normal pentenes, or other gases, is contacted with a mass consisting essentially of silicon carbide at an elevated temperature for a time sufficient to effect a desired extent of conversion to 1,3 cyclopentadiene.

As stated, the contact mass employed, according to the invention, is essentially silicon carbide. A silicon carbide which has been found suited to the practice of the invention is sold in the trade by The Carborundum Company. Obviously

2

equivalent silicon carbides can be employed. The contact mass is preferably in a sub-divided state. Particles having a cylindrical shape and measuring $\frac{1}{8}$ inch in diameter as well as length have been employed. Other sizes can be employed, the essential condition being good contact between the hydrocarbon compound and the contact mass. Also, the contact mass should not cause too great a pressure drop through the conversion tube for practical operation reasons.

The temperature employed for the dehydrogenation of the hydrocarbon, in the instant case 1,3 pentadiene, will vary depending upon the other conditions of operation and on the nature or purity of the charging stock. However, the conversion of 1,3 pentadiene can be advantageously effected at a temperature within the range 300° C. to a temperature above which substantial decomposition of the hydrocarbons will

10 take place. More specifically a temperature within the range 400° C.—700° C., preferably 450° C.—650° C., can be employed.

While the conversion per pass is substantially independent of pressure it has been found that 15 lower pressures seem to form higher yields on recycling. Accordingly, while higher and lower pressures are not excluded from the scope of the invention, pressures in the range of 1000 mm. Hg—10 mm. Hg, preferably 200 mm. Hg—10 mm.

20 Hg, can be employed.

Example I

One thousand grams of 1,3 pentadiene were charged at a rate of 5 grams/minute, at a pressure of about 30 mm. Hg, to 1000 grams of a mass, consisting of silicon carbide, in a conversion tube at a temperature of 600° C. The effluent from the conversion tube was cooled, condensed and fractionated, resulting in a yield of 39.0 grams of 35 40 45 50 55 1,3 cyclopentadiene. On recycle of the unconverted 1,3 pentadiene the yield is 440 grams.

Example II

One thousand grams of 1,3 pentadiene were charged at a rate of 5 grams/minute, at a pressure of about 15 mm. Hg, to 1000 grams of a mass, consisting of silicon carbide, in a conversion tube at a temperature of 610° C. The effluent from the conversion tube was cooled, condensed and fractionated, resulting in a yield of 50.4 grams of 1,3 cyclopentadiene. On recycle of the unconverted 1,3 pentadiene the yield is 475 grams.

The contact mass can be regenerated indefinitely to substantially its original activity.

It will be apparent to those versed in the art that wide modification and variation is possible within the scope of the invention as defined in the appended claims, the essence of the invention being that n-pentane, 1-pentene, 2-pentene and/or 1,3 pentadiene can be dehydrogenated and cyclized by contacting the same at elevated temperature and suitable pressure with silicon carbide as set forth herein and in the appended claims.

What we claim and desire to protect by Letters Patent is:

1. A process for the dehydrogenation and cyclization to 1,3 cyclopentadiene of 1,3 pentadiene which comprises subjecting said compound to a dehydrogenation temperature within the range 300° C. to a temperature above which substantial decomposition of the hydrocarbons will take place in the presence of a contact mass consisting essentially of silicon carbide for a time sufficient to cause a desired extent of conversion to cyclopentadiene.

2. A process according to claim 1 wherein the temperature is within the range 450° C.-650° C. and the pressure is within the range 200 mm. Hg-10 mm. Hg.

ROBERT M. KENNEDY.
STANFORD J. HETZEL.
